UNITED STATES PATENT OFFICE.

LEONARD D. KROFF, OF STERLING, ILLINOIS, ASSIGNOR TO FIRST TRUST AND SAVINGS BANK OF STERLING, OF STERLING, ILLINOIS, A CORPORATION OF ILLINOIS.

GAME BOARD FOR BASEBALL.

Application filed April 20, 1920. Serial No. 375,211.

To all whom it may concern:

Be it known that I, LEONARD D. KROFF, a citizen of the United States, residing at Sterling, in the county of Whiteside and State of Illinois, have invented certain new and useful Improvements in a Game Board for Baseball, of which the following is a specification.

My invention has reference to a game board for baseball, and is specially constructed and arranged for playing a game of ball by mechanical means. It can, however, be adapted for the playing of other well-known and popular games, such as football, cricket, etc.

It is a recognized fact that in the game of baseball, as generally played, there are eight fixed conditions, depending upon the positions of the players. These are, bases empty; man on first base; man on second base; man on third base; men on first and second bases; men on first and third bases; men on second and third bases; and bases full. Included with each of these conditions is a man at bat at the home plate. In connection with these conditions are a great variety of plays which go to make up the game.

The chief purposes of the invention is to provide a stationary indicator showing the eight conditions referred to, and a movable indicator containing a variety of plays, so that certain ones thereof will apply to and be controlled by, one or other of the fixed conditions.

Another purpose of the invention is to provide a simple, compact, and efficient apparatus by means of which the game may be played.

The preferred form of the device is shown in the drawings, in which:

Fig. 1 is a plan view of my invention, at a slight angle, as shown by the arrow in Fig. 2.

Fig. 2 is a longitudinal section thereof.

Fig. 3 shows the permanent indicator, and a fractional part of the movable indicator chart, in their relative positions.

Fig. 4 shows one of the men by means of which the game can be played.

The apparatus comprises a frame 1, in one end of which is rotatably mounted a shaft 2 upon which is secured a cylinder 3. Fixed to one end of said shaft is a toothed wheel 4, engaged by a spring arm 5 on the

end of a lever 6, pivoted in one side of the frame, as at *a*. The lever 6 is held yieldably in elevated position by means of a spring 7, connected at one end to the lever and at the other end to the frame 1. Said lever can be forced downwardly by means of a push-pin 8, passing through an opening 9 in a plate 10 supported in the forward part of the frame 1. When the lever is forced downwardly by the operator the arm 65 5 imparts rotation to the wheel 4 and cylinder 3, such arm passing downwardly out of range of the teeth, permitting the cylinder to rotate freely from the momentum thereof. 70

At the inner end of the plate 10 is an inclined cross-piece 11, and encircling the cylinder 3 is a hood 12, the forward edge of which is spaced apart from the upper edge of the cross-piece 11. Attached to said cross-piece, near its upper edge, is a strip 13, divided into eight spaces 14, each containing a designation of one of the conditions of the game hereinbefore mentioned, such designations being preferably arranged in progressive order, from one side to the other. Attached to the cylinder 3 is a chart, made up of eight columns of spaces, each of said spaces containing wording to designate a play in the game, each of said columns containing a variety of such plays, such as would ordinarily occur in a game of baseball. The arrangement is such that one of the lines of spaces 16 will be visible at a time through the space between the cross-piece 11 and hood 12, as clearly appears in Fig. 1. 85

The upper part of the plate 10 is provided with a representation of a baseball diamond, as shown at 17, and such other features connected with the game as may be desired. To facilitate the playing of the game players 18 can be employed, of two different kinds or colors, and sufficient in number to represent the requisite number 100 of players on each side of the game.

To play the game, one of the pieces 18 is placed on the home plate of the diamond, and the pin 8 pushed downwardly by the finger of the player. This causes the cylinder 3 to rotate, and such rotation may be permitted to continue until the wheel stops of its own accord, or it can be checked by removing the finger, letting the lever return to its former position. In any case, the 110

finger is removed before the play is completed, the return movement of the lever causing the arm 5 to re-engage the teeth of the wheel 4, and carry such wheel rearwardly the distance of three or four teeth. This prevents any manipulation of the wheel, which might be attempted, in order to get it to stop at some desired point in its rotation.

- 10 Upon the wheel being stopped, one of the lines on the chart 15 is visible, as before stated. On this line eight different plays are indicated, however, but each of said plays relates to a different condition of the game. In the present case, with the game just starting, the character of the play is indicated and governed by the first space at the right on the permanent indicator, or "bases empty." The play will then be a strike, ball, or whatever play is indicated in the column corresponding with that condition. If the play is a one base hit, the player is advanced to first base, and another batter provided. The play is now governed by the second column, or "man on 1st." The designations on the movable indicator now differ from those on the first column, as it is frequently necessary to show two plays, as for instance, "one base hit, and man to 3rd, or home." In case of the play being a base hit, and man to third, then the next play is controlled by the column headed "Man on 1st and 3rd." If the bases are all occupied, the last column at the left determines the nature of the play.

The selection and arrangement of the various plays on the chart is purely arbitrary, it being necessary to provide some forty or more of such designations in each column to cover all of the chances of an ordinary game.

In playing the game, one side plays until three men are out, when the other side has an inning in the usual way. Regular tally sheets can be kept, if desired, and the pitcher, catcher, and other players of the out team arranged on the field in the usual positions. If desired, the pieces used in playing the game can be numbered, or otherwise marked to correspond with the players of well-known ball teams.

In games of ordinary size it will be necessary to abbreviate the words on the indicators, and contract the diamond and field, but in those of larger size it will not be necessary to do this.

What I claim and desire to secure, is:

1. In a game apparatus, a frame having a top portion upon which the game field is displayed, a housing at one edge of said top portion, said housing having a window, a permanent indicator lying along the longitudinal edge of said window and having spaces containing indicia of the principal conditions of the game, an indicator cylin-

der rotatable in said housing and having circumferential columns and longitudinal rows of "plays" on its periphery corresponding to the spaces of said permanent indicator, one longitudinal row being visible at a time through said window, means for manually turning said cylinder, said means comprising a toothed wheel on one end of the cylinder, a lever fulcrumed on said frame and having a tooth to engage said toothed wheel, spring means normally holding said lever in raised position with its tooth engaged with the wheel, means for manually depressing said lever so as to disengage it from said toothed wheel and give a turning impulse to said cylinder to rotate the same freely, said lever adapted to re-engage and lock the wheel when released.

2. In a game apparatus, a frame having a top portion upon which the game field is displayed, a housing at one edge of said top portion, said housing having a window, a permanent indicator lying along the longitudinal edge of said window and having spaces containing indicia of the principal conditions of the game, an indicator cylinder rotatable in said housing and having circumferential columns and longitudinal rows of "plays" on its periphery corresponding to the spaces of said permanent indicator, one longitudinal row being visible at a time through said window, means for manually spinning said cylinder, said means comprising a toothed wheel on one end of the cylinder, a lever fulcrumed on said frame and having a tooth to engage said toothed wheel, spring means normally holding said lever in raised position with its tooth engaged with the wheel, means for manually depressing said lever so as to disengage it from said toothed wheel and give a turning impulse to said cylinder to rotate the same freely, said lever adapted to re-engage said wheel, impart a limited reverse rotation thereto and then lock said wheel, when said lever is released.

3. A game apparatus of the character specified, comprising a casing having a top portion upon which the game field is displayed, a rotatable cylinder in the casing at one edge of the field and bearing upon its periphery "plays" arranged in circumferential columns and longitudinal rows, said casing having a longitudinal sight opening adjacent the cylinder through which one of the rows of "plays" is visible and a row of directions adjacent the opening, there being one direction for each column of "plays" on the cylinder, a toothed wheel on the cylinder, a lever having a tooth engaging said toothed wheel, spring means for normally holding the lever in raised position with its tooth engaged with the wheel so as to lock the cylinder, means for manually depressing said lever so as to disengage it from the

toothed wheel and cause rotation of the cylinder, the lever re-engaging and locking the wheel when released.

4. A device of the class described, comprising a frame; a shaft rotatably mounted in one end thereof; a cylindrical member secured to said shaft; a toothed wheel fixed to said shaft; a spring-controlled lever operatively associated with said wheel, to cause a 10 rotation of said cylinder at times and to lock said cylinder against rotation at other times; a plate mounted in said frame, bearing the representation of the field upon which the game is played; a permanent indicator on 15 said frame, showing a series of the principal conditions thereof; and a plurality of plays of the game on said cylinder, arranged in columns corresponding with the permanent designations.
- 20 5. In a device of the class described, a frame; a shaft rotatably mounted therein; a cylinder secured on said shaft showing a plurality of plays in a game, arranged in lines laterally of said cylinder and in columns circumferentially thereof; an indicator on said frame, showing the principal conditions under which the game is played, arranged to correspond with said columns; a cover for said cylinder, having an opening 25 through which one of the lines on said cylinder can be disclosed at a time; and manually operated means for rotating said cylinder so that upon the same being stopped one of said lines will be visible through said 30 opening and a spring device cooperating with said means for stopping said cylinder.
6. In a device of the class described, a frame; a shaft rotatably mounted therein; a cylinder carried by said shaft, showing a 35 plurality of plays in the game, arranged in lines laterally of the cylinder, and in columns circumferentially thereof; a cover for said cylinder, having an opening through which one of said lines can be disclosed at 40 a time; a toothed wheel on said shaft; a spring-controlled lever normally in engagement with said wheel, and adapted when thrust in one direction to impart complete rotation thereto, the return movement of 45 said lever operating to give said wheel a partial reverse rotation; and an indicator on said frame, containing the principal conditions under which the game is played, arranged to coincide with the columns on said 50 cylinder.
- 55 7. In a game apparatus of the character specified, a casing having a top portion upon which the game field is displayed, a rotatable cylinder in the casing at one edge of the field bearing upon its periphery "plays," a permanent indicator on the top adjacent to said cylinder showing the principal conditions of the game and cooperative with the cylinder and game field, a lever fulcrumed at one end at another edge 60
- of said casing and having a bent tooth element at its free end, a toothed wheel on said cylinder with which said bent tooth element is adapted to engage, a spring for holding said lever in the normal position with its tooth element in engagement with said toothed wheel to lock said cylinder against rotation, and a finger piece to engage said lever for depressing the same to thereby cause rotation of said cylinder and move 70 said tooth element out of engagement with said toothed wheel to permit said cylinder to spin, the aforesaid parts being so arranged that upon release of said lever said tooth element will engage said toothed wheel 75 and impart a partial reverse rotation to said cylinder before locking the same.
8. In a game apparatus embodying a frame and cylinder rotatable in one end thereof, a toothed wheel on one end of the 80 cylinder; a lever having a tooth engaging said toothed wheel; spring means for normally holding the lever in raised position with its tooth engaged with the wheel; and means for manually depressing the lever so as to disengage it from the toothed wheel 85 and cause the cylinder to spin, the lever re-engaging and locking the wheel when released.
9. In a game apparatus of the character 90 described, a rotatably mounted cylinder, a toothed wheel on the cylinder, a lever having a tooth engaging said toothed wheel, spring means for normally holding the lever in raised position with its tooth engaged with the wheel so as to lock the cylinder, and means for manually depressing the lever 95 so as to remove it from the path of rotation of said toothed wheel and permit the cylinder to rotate freely; the lever reengaging and locking the wheel when released.
10. In a device of the class described, a frame; a shaft rotatably mounted therein: a cylinder carried by said shaft, showing a plurality of plays in the game, arranged in 100 lines laterally of the cylinder, and in columns circumferentially thereof; a cover for said cylinder, having an opening through which one of said lines can be disclosed at a time; a toothed wheel on said 105 shaft; a spring-controlled lever normally in engagement with said wheel and adapted, when depressed, to spin said wheel and cylinder, the return movement of said lever operating to give said wheel and cylinder a 110 partial reverse rotation; and an indicator on said frame, containing the principal conditions under which the game is played, arranged to coincide with the columns on said cylinder.
11. In game apparatus, a rotatably mounted cylinder, a toothed wheel on the cylinder, a lever having teeth engaging said toothed wheel, spring means normally holding the lever in raised position with the 115
- 120
- 125
- 130

teeth engaged with the wheel so as to lock the cylinder, means by which said lever may be manually depressed to disengage it from said toothed wheel and thereby impart a spin to said toothed wheel during the interval that said toothed wheel is disengaged from said cylinder, said lever re-engaging and locking said wheel, when released.

12. In game apparatus of the character described, a support, a cylinder mounted on said support, said cylinder having a plurality of V-shaped teeth, a lever fulcrumed on said support, and having its end provided with a projection to engage said teeth, a spring for holding said lever in one position to engage said teeth and lock said wheel against movement and finger operated means for moving the lever against tension of the spring through an arc sufficient to disengage it wholly from said teeth and thereby impart spinning motion to said cylinder while said lever remains depressed, for the purposes specified.

13. In game apparatus of the character described, a support, a cylinder mounted on said support, said cylinder having a plurality of V-shaped teeth, a lever fulcrumed on said support, and having its end provided with a projection to engage said teeth, a spring for holding said lever in one position to engage said teeth and lock said wheel against movement and finger operated means for moving the lever against tension of the spring through an arc sufficient to disengage it wholly from said teeth and thereby impart spinning motion to said cylinder while said lever remains depressed, said lever and said teeth being so arranged that upon return of said lever under spring action it will again engage the teeth of said cylinder and impart a limited backward rotation to said cylinder before locking the same.

14. A game apparatus of the character specified comprising a casing having a top portion marked to indicate a game field, a rotatable cylinder in the casing at one side of the field bearing upon its periphery indicia indicating "plays" arranged in circumferential columns and longitudinal rows, the casing having a longitudinal sight

opening adjacent the cylinder through which one of the rows of "plays" is visible, said casing bearing a row of indicia indicating the condition of the "bases" on the field, there being one indication for each column on the cylinder, a toothed wheel on the cylinder, a lever having a tooth engaging said toothed wheel, spring means for normally holding the lever in raised position with its tooth engaged with the wheel so as to lock the cylinder, and means for manually depressing the lever so as to disengage it from the toothed wheel and permit the cylinder to rotate; the lever reengaging and locking the wheel when released.

15. A game apparatus comprising a casing having indicia for a baseball field on its top, and having indicia at the sides of the field indicating the "benches" and having indicia along the edges of the field for the placement of "out" players, playing pieces adapted to cooperate with said indicia; a rotatable cylinder along one edge of the field extending longitudinally thereof and rotatably mounted in the casing, said cylinder bearing on its periphery circumferential columns with indicia indicating acts to be performed upon the field, the "plays" in adjacent columns being also arranged in rows extending longitudinally of the cylinder; a cover for the cylinder provided with a longitudinal sight opening through which one longitudinal row of "plays" on the cylinder may be read; and a series of indicia designating the condition of the "bases" of the field, located adjacent to said sight opening by which different "plays" are governed, there being one indicia for each column of "plays," a toothed wheel on the cylinder, a lever having a tooth engaging said toothed wheel, spring means for normally holding the lever in raised position with its tooth engaging with the wheel so as to lock the cylinder, and means for manually depressing the lever so as to disengage it from the toothed wheel and permit the cylinder to rotate; the lever reengaging and locking the wheel when released.

In testimony whereof I affix my signature.
LEONARD D. KROFF.
